UNITED STATES PATENT OFFICE

WALTER REMPEN, OF HANOVER, GERMANY, ASSIGNOR TO AARON M. SLOSS, OF NEW YORK, N. Y.

HEATING STOVE

Application filed January 28, 1929, Serial No. 335,662, and in Germany April 23, 1924.

This invention relates to a stove intended for heating rooms and the like, also for generating steam for steam-heating plants, and for burning disintegrated lignite coke in it. 5 This improved stove is so designed that it can be charged particularly easily which is rendered possible by the provision of a particularly designed charging device known, it is true, already in connection with lignite coke ovens, but being herein accommodated to stoves in a very practical manner. The fuel is conveyed into the combustion chamber of the stove upwardly by means of a worm arranged in the lowermost part of the same. 10 15 The worm can be turned or rotated by any desired means, for instance by means of a vertical shaft extending from the conveying worm upwardly through the stove and being provided at its upper end with a grip or crank or the like. Feeding the conveying worm with the disintegrated fuel can be effected in any desired manner, preferably in the same manner as in lignite coke ovens having a coke conveying worm. Feeding the 20 25 fuel into the combustion space of the stove by means of the worm is particularly useful in the case of room stoves in that no shovels need be used and no dust is produced.

As the stove has no oven it is devoid of 30 cooking and roasting spaces, and it is, therefore, possible to provide a fuel storage space also above the combustion chamber. In this case the worm shaft or at least that part of it which is located between the worm and 35 said upper fuel space is made hollow, and the upper fuel is conducted to the lower fuel through that hollow shaft or hollow portion of the shaft so that the upper fuel is also conveyed into the combustion space by the intermediary of the worm.

The efficiency of the stove can be increased by the provision of holes in the bottom of the combustion space so that air, i. e. combustion air, can find direct access to the burning 40 or glowing lignite coke.

The invention is illustrated diagrammatically and by way of example on the accompanying drawing which shows a vertical axial section through a stove designed according to this invention.

The conveying worm *a* is arranged in the lowermost part of the stove and affixed to a hollow shaft *b* which extends upwardly through the combustion space and the upper end of which is shaped somewhat like a hopper. 55 This hopper-like end of the hollow shaft *b* is connected with the lower end of a vertical solid shaft *e* by means of a so-called arrin-cross *d*. The upper end of the shaft *e* is provided with a crank *f*, by means of which the shafts *e* and *b* can be turned or rotated, the direction of rotation being always such that the disintegrated lignite coke supplied to the worm *a* is conveyed upwardly 60 by this latter into the combustion space. 65

The hopper *c* is in close contact with the lowermost portion *g* of the funnel-shaped bottom of a vertical receptacle *h* which is a storage receptacle for the disintegrated lignite coke. When the crank *f* is turned, the arms 70 of the cross *d* causes a certain amount of the coke to fall down into and through the hollow shaft *b* to the space containing the worm *a*. As the worm is turned or rotated, the coke is now also conveyed upwardly into the 75 combustion space, as already explained.

Below the hopper *c* a curved scraper *i* is affixed to the shaft *b*, and just above the perforated bottom plate *l* of the combustion space a stirring arm *k* is also secured to the shaft *b*. *m* denotes the perforations of the plate *l*. The combustion space is formed by this plate and by a bell-shaped ceiling *o* below which the fuel forms a hill *n*. As the shaft *b* is revolved to operate the feed screw 80 *a*, the scraper *i* revolves with the shaft and it serves to dislodge the ash formed by the combustion of the fuel on the top of the pile *n* so that the ash works down and passes through the apertures in the plate *l* into the ash compartment *t*. The stirring arm *k* also 85 revolves with the shaft *b* and it serves to stir or break up the fuel which is fed upwardly by the screw *a*. The hot combustion gases pass away from the top of the fuel hill *n* 90 into a tubular space *p* formed by and between the outer wall of the stove and an inner wall *r* located between said outer wall and the coke receptacle *h*. The other tubular space 95 formed by and between this receptacle and

the inner wall *r* forms an air passage which communicates with the air in the room through apertures *s*. The fresh air to be heated enters through bottom apertures, as indicated by the arrows. These apertures receive the fresh air through the annular passage *q*. *t* represents a chamber comprising an ashpit to receive the ashes falling through the apertures *m* in the plate or grate *l*.

10 The fuel contained in the receptacle *h* is always dry, as it is heated (preheated) by the hot combustion gases, and owing to its dryness it is prevented from obstructing the tubular passage *b* and is always reliably conducted thereinto when the shaft *e* is turned.

15 I claim:

1. A heating stove for burning disintegrated lignite coke, comprising, in combination, with the stove body and a combustion chamber in the lower part thereof, a fuel storing vessel arranged over said chamber whereby it is heated by the fuel burned in said combustion chamber, means for conveying the fuel from said vessel to a space below the said combustion chamber, and a fuel conveying worm so arranged below said combustion chamber as to be adapted to convey the fuel thereinto.

2. A heating stove for burning disintegrated lignite coke, comprising, in combination, with the stove body and a combustion chamber in the lower part thereof, a fuel storing vessel arranged below said chamber, a tubular shaft extending from the lower end of said vessel to a space below the said chamber and adapted to conduct the fuel from above to below, a worm secured to that part of said shaft which is located below the combustion space, and means for turning the said shaft with the worm.

3. A heating stove for burning disintegrated coke, comprising, in combination with the stove body and a combustion chamber in the lower part thereof, a fuel storing vessel arranged below said chamber, a tubular shaft extending from the lower end of said vessel to a space below the said chamber and adapted to conduct the fuel from above to below, a worm secured to that part of said shaft which is located below the combustion space, a vertical solid shaft connected at its lower end with the upper end of said tubular shaft and extending upwardly through the said storing vessel, and means for turning said solid shaft, substantially as set forth.

4. A heating stove for burning disintegrated lignite coke, comprising, in combination with the stove body and a combustion chamber in the lower part thereof, a perforated plate forming the bottom of said chamber and having a large central opening, a tubular shaft extending from the lower end of said vessel to a space below the said chamber and adapted to conduct the fuel from above to below, a worm secured to that part

of said shaft which is located below the combustion space and having a diameter corresponding to that of said large opening, and means for rotating said worm.

5. A heating stove for burning disintegrated lignite coke, comprising, in combination with the stove body and a combustion chamber in the lower part thereof, a perforated plate forming the bottom of said chamber and having a large central opening a fuel storing vessel arranged over said combustion chamber, a tubular shaft extending from the lower end of said vessel to a space below the said chamber and adapted to conduct the fuel from above to below, a worm secured to that part of said shaft which is located below the combustion space and having a diameter corresponding to that of said large opening; a vertical solid shaft connected at its lower end with the upper end of said tubular shaft and extending upwardly through the said storing vessel, and a crank secured to the upper end of this shaft, substantially as set forth.

In testimony whereof I affix my signature.

WALTER REMPEN.
